EDGAR E. GREVE, OF BELLEVUE, PENNSYLVANIA.

TONG SUPPORT FOR EARTH-BORING APPARATUS.

Application filed November 8, 1922. Serial No. 599,669.

This invention is for a tong carrying means for use in connection with rotary earth drilling rigs, and relates particularly to a tong support for allowing a pipe engaging tong to move vertically with the pipe which it is turning in the operation of screwing sections of pipe or drill-stem together.

In rotary drilling operations, the drill stem is composed of sections of pipe connected together. As the depth of the hole increases, sections of pipe must be added, necessitating frequent screwing and unscrewing of threaded connections. The rotaries used in such drilling operations are arranged in such manner that a power driven part of the rotary may be utilized in rotating a pipe wrench attached to a pipe section for screwing and unscrewing the pipe sections. When a tong is thus attached to a pipe, it must be free to move vertically with the vertical movement of the pipe as it screws into or out of the threaded joint.

The present invention has for its principal object to provide a tong support which will allow the tong to move vertically while it is rotating the pipe, and which will allow for this movement without binding.

The invention may be readily understood by reference to the accompanying drawings, 30 in which:

Fig. 1 illustrates a side elevation of my invention, showing it applied to a rotary, the rotary being shown in section;

Fig. 2 is a side elevation of a slight modification;

Figs. 3 and 4 are views similar to Fig. 2, showing other modifications.

In the drawings, A designates the rotary having a drive ring 5 and a table 6, the rotary being of any known or preferred construction. The pipe or drill stem is designated in all figures of the drawings as B.

The drive ring 5 is provided with a socket or other suitable means 7 for removably holding a vertical post 8, the post preferably being received in the socket or supported in such manner that it may swivel or rotate on its longitudinal axis. The top of the post 8 is preferably enlarged at 9 and bifurcated, the bottom of the intervening space being inclined, as indicated by the dotted line 10 of Fig. 1.

Received within the bifurcated end of the post is a lever 11 having a slot therein, 55 through which a pin, or a pin and roller,

12 passes, thus providing a sliding pivotal support for the lever. One end of the lever, hereinafter termed the inner end of the lever, is pivotally connected at 13 with a tong supporting member 14, which member preferably takes the place of the ordinary handle for the tong, said member having the jaws 15 pivotally connected therewith in the usual manner. A lip 16 extends from the connecting member 14 beneath the pivoted joint at the lower end of the lever, thus preventing the tong comprised of jaws 15 from sagging or hanging down relatively to the lever when the latter is in a horizontal position and before attachment to the drill 70 stem.

If the tong is attached to a pipe section which is to be screwed into another pipe section, the tong is attached to the pipe section with the lever in a horizontal position. Then, as the pipe moves downwardly as it screws into the joint, the tong may move with the pipe, rocking the lever. The sliding pivotal mounting provided for the lever enables the tong to move downwardly coaxially with the pipe at a proper distance from the post, not being moved toward the post by the arcuate movement of the lever.

In order to normally hold the lever 11 in a horizontal position, some means is provided for counteracting the weight of the tong. In Fig. 1, I have shown a tension spring 17 connected at one end to the outer end of lever 11 and at its other end to suitable securing means, such for instance, as lug 18 on the post 8. The slope of the bottom face of the post 8, where it is bifurcated, enables one end of the lever to tilt downwardly from a horizontal position, but prevents the outer end from moving downwardly any substantial distance beyond the horizontal.

The construction in Fig. 2 is similar to that shown in Fig. 1, with the exception of the spring means for returning the lever to horizontal position. In this figure, I have shown a rod 19 passed through an opening in the post 8 and secured at 20 to the lever. A compression spring 21 surrounding the rod, confined between the lever and a seat in the post, serves to hold the lever in horizontal position.

The lever may be weighted at its outer end instead of being spring actuated. While this might be done in several ways, I have

shown a rod 22 having a sliding pivotal connection at 23 with the outer end of lever 11. The rod is pivotally connected at its lower end with post 8 at 24. The rod as thus provided does not interfere with the swinging sliding movement of lever 11. This rod acts as a guide for weight 25, suspended by link 26 from the outer end of lever 11, said weight being slideable on the rod. The rod 10 holds the weight from swinging out under the action of centrifugal force. The weight, being freely slideable on the guide rod, always urges the lever 11 toward its horizontal position.

15 In Fig. 4, I have shown a leaf spring in place of the coil springs of Figs. 1 and 2. This leaf spring, designated 28, is fixed in the post at 29, and has its outer end bearing against the under side of the inner end 20 of lever 11, thereby urging it upwardly.

Various other arrangements for returning the lever to horizontal position are contemplated, and various changes and modifications may be made in the construction of the 25 device within the contemplation of the invention and within the scope of the appended claims.

I claim as my invention:

1. A tong support for use in connection 30 with rotary drilling operations comprising a post, a transverse lever pivotally carried by the post movable on a horizontal axis, a tong carried at the inner end of the lever, and means for counteracting the weight of 35 the tong.

2. A tong support for use in connection 40 with rotary drilling operations comprising a post, a transverse vertically swinging lever pivotally carried by the post, a tong supporting means pivotally carried at the inner end of said lever, and means for counteracting the weight of the tong.

3. A tong support for use in connection 45 with rotary drilling operations comprising a vertical member, a transverse horizontally pivoted lever carried by the vertical member, a tong pivotally carried at the inner end of the lever, and means for allowing a lateral movement of the tong toward and 50 away from the pivotal support for said lever with the arcuate movement of said lever.

4. A tong support for use in connection 55 with rotary drilling operations comprising a supporting structure, a horizontally pivoted lever carried thereby, tong supporting means pivotally carried at the inner end of the lever on a horizontal pivot, and means for preventing the tong carrying means 60 from swinging downwardly relatively to the lever when the latter is in a horizontal position.

5. A tong support for use in connection 65 with rotary drilling operations comprising a post, and a tong supporting lever pivot-

ally carried by the post and arranged to swing in a vertical plane, said lever being arranged to swing downwardly from a horizontal position in one direction, but being limited against rocking past a substantially 70 horizontal position in the other direction.

6. A tong support for use in connection 75 with rotary drilling operations comprising a post, and a tong supporting lever pivotally carried by the post and arranged to swing in a vertical plane, said lever being arranged to swing downwardly from a horizontal position in one direction, but being limited against rocking past a substantially 80 horizontal position in the other direction, 85 said lever having a slideable pivoting mounting in the post.

7. A tong support for use in connection 90 with rotary drilling operations comprising a supporting means, a lever mounted in said supporting means and arranged to swing in a vertical plane, said lever being adapted to carry a tong at one end thereof, and means for urging said lever to a predetermined normal position.

8. A tong support for use in connection 95 with rotary drilling operations comprising a supporting means, a lever mounted in said supporting means and arranged to swing in a vertical plane, said lever being adapted to carry a tong at one end thereof, and means for counteracting the weight of a tong carried by the lever for urging said lever to a substantially horizontal normal position.

9. A tong support for use in connection 100 with rotary drilling operations comprising a supporting means, a lever mounted in said supporting means and arranged to swing in a vertical plane, said lever being adapted to carry a tong at one end thereof, and means for yieldably counteracting the weight of a 105 tong carried by the lever for urging said lever to a substantially horizontal normal position.

10. A tong support for use in connection 110 with rotary drilling operations comprising a supporting means, a lever mounted in said supporting means and arranged to swing in a vertical plane, said lever being adapted to carry a tong at one end thereof, 115 means for yieldably counteracting the weight of a tong carried by the lever for urging said lever to a substantially horizontal normal position, and means whereby the tong carrying end of said lever may move coaxially with a pipe to be engaged.

11. A tong support for use in connection 120 with rotary drilling operations comprising a supporting structure, a transverse lever carried thereby and movable in a vertical 125 plane in one direction only from a normal substantially horizontal position, tong carrying means at the downwardly movable end of said lever, means whereby said tong carrying means may move co-axially with 130

a straight pipe to be engaged as said lever is rocked, and means for yieldably urging the lever to the substantially horizontal normal position.

5 12. A tong support for use in connection with rotary drilling operations comprising a post, a horizontally pivoting arm carried

by the post, and resilient means connected to the arm for urging the arm upwardly against gravity to a normal position, and 10 a tong carried by the arm.

In testimony whereof I affix my signature.

EDGAR E. GREVE.
